ILLUMINATED UMBRELLA

Filed Oct. 12, 1943

UNITED STATES PATENT OFFICE

2,372,471

ILLUMINATED UMBRELLA

Anna L. Campbell, Feasterville, Pa.

Application October 12, 1943, Serial No. 505,987

1 Claim. (Cl. 135—47)

My invention relates to an umbrella, and relates particularly to an umbrella having a ray emitting device which is visible in the darkness.

In my prior Patent No. 2,246,836 patented June 24, 1941, I disclose an umbrella wherein the staff or stick is made of a methacrylic resin or acrylic acid product sold under the trade-mark "Lucite" which staff or stick transmits rays of light therethrough.

My present invention provides for an umbrella wherein the covering is elevated or lowered by mechanism which does not in any manner obstruct the passage of light rays through the staff or stick, and wherein the canopy or cover may be held in an open or a closed position.

It is, therefore, an object of my invention to provide in an umbrella a staff or stick which possesses good optical properties for the passage of light rays, a covering or canopy that may be locked in an elevated or a lowered position without in any manner obstructing the passage of light rays, and which has a suitable source of electricity for creating the light rays.

It is another object of my invention to provide in an umbrella a staff made of a non-breakable, flexible, sturdy material, which may be easily molded or machined, which will not collect dirt, and which need not be painted since the material of the staff may be dyed.

Other objects of my invention are to provide an improved device of the character described, that is easily and economically produced, which is sturdy in construction, and which is highly efficient in operation.

With the above and related objects in view, my invention consists in the details of construction and combination of parts, as will be more fully understood from the following description, when read in conjunction with the accompanying drawing, in which:

Fig. 1 is a front elevational view of an umbrella embodying my invention with the covering and supporting ribs removed.

Fig. 2 is a sectional view taken on the line 2—2 of Fig. 4.

Fig. 3 is an end view taken on the line 3—3 of Fig. 4.

Fig. 4 is a fragmentary view of the umbrella with the covering or canopy and supporting ribs omitted for clarity of observation.

Fig. 5 is a view of a complete umbrella embodying my invention.

Referring now in detail to the drawing, I show an umbrella which includes a staff or stick, generally designated as A, made of a methyl meth-

acrylate resin or acrylic acid product, also sold under the trade-mark "Lucite" wherein rays of light can be transmitted through the stick. The stick A is relatively long as compared to its diameter and is threaded at each of its ends 10, 12. One threaded end 10 of the staff A receives a hollow handle, generally designated as B, which is larger in diameter than the stick, and wherein a push button controlled light ray unit is housed. The flash-light unit or light ray unit furnishes the rays of light which illuminate the staff or stick A.

An electric light bulb 14 is screwed within a casing 16 which casing abuts against a corner of the battery chamber 18, and one end of the bulb abuts against an electric battery 20. A spring pressed-wire conductor 22 contacts the outside of the battery when a push button 24 is pressed thereby completing the electric circuit through the metallic cylindrical wall 16 which surrounds the battery 20 and the cylindrical wall extends from the spring contact 22 to the bulb casing 16.

The battery 20 rests on an insulating disk 28 in order to prevent the electric circuit from being continually completed; if this were the case then the life of the battery would be relatively short because it would soon become inactive. When the push button 24 is pressed inwardly the electric circuit through the electric bulb 14 is completed through the conductor 22 which is electrically connected to the metallic wall 26, and the bulb casing 16.

A cap 30 making a threaded engagement with the handle B holds the metal battery cylinder 16 in position, and the cap 30 has a central opening 32 therein so that the push button 24 may pass freely through the opening.

Adjacent the handle B is a stationary locking member, generally designated as C, which has a portion 34 tightly gripping and embracing the stick A; another portion 36 of the stationary locking member C is of a larger diameter than the stick gripping portion 34 so that it is spaced from the stick to form a cover for one hook 38 of a double hook, generally designated as D. The canopy closing hook 38 is adapted to fit between the stick A and the large diameter locking member 36 which forms a catch or clasp 40 for a slidable closing member, generally designated as E, to which the hook 38 is attached when the canopy is to be held in a closed position. A suitable opening 42 in the stationary locking member C defines the catch 40 and receives a bent portion 56 of the hook so that a locking relationship exists

between the hook 38 and the stationary locking member C.

The hook D is pivotally mounted at 44 to the slidable closing member E and is integrally attached to a second hook 46 which is adapted to engage and hook upon a stationary anchoring member, generally designated as F, in order to keep the canopy or cover, generally designated as G, in an open position.

The slidable closing member E is a cylindrical member slid in a longitudinal direction along the stick A. Radially extending from the cylindrical member E is a pair of spaced rib anchoring members 48, 50 for the purpose of holding ribs (not shown), which are engaged intermediate the ends 15 of canopy supporting ribs (not shown).

The double hook or double latch D is pivoted at substantially its center 44 to the slidable closing member E and has one hook or latch 38 pressed outwardly by a spring 52 so that each hook 38 and 46 has a tendency to grasp its complementary stationary locking catch or keeper 40 and 54 respectively.

The rib anchoring member F tightly grasps the outside of the stick A near the tip of the stick 25 and the rib anchoring member F has the keeper 54 integrally formed therewith to receive the closing latch, lock or hook 46.

It is to be noted that the slidable closing member E, the stationary locking member C, or the rib anchoring member F have no portion thereof pierce the stick A, hence the passage of rays of light through the stick is not hindered.

Different colored disks may be placed across the top of the bulb to give or produce different color effects through the transparent stick A.

An enlarged tip 56 is threadedly engaged to the end of the stick A to enlarge the dispersion of light which is directed through the stick A, thus

from a small light source a relatively large light is visible.

My invention may be applied to a rain type of umbrella or even a beach umbrella, and the light source, contained in the handle B may be removed and used alone simply by unscrewing the handle B, or if a bayonet joint is used to turn the handle B, or if a bayonet joint is used between the handle and stick then it is only necessary to turn the handle to separate the handle and stick. The control push button 24 also may be located on the side instead of the end of the handle.

Although my invention has been described in considerable detail, such description is intended as illustrative rather than limiting, since the invention may be variously embodied, and the scope of the invention is to be determined as claimed.

I claim as my invention:

An umbrella comprising a transparent stick for transmitting light rays, means in said umbrella to create light rays, a stationary locking member, mounted on said stick, and tightly gripping the outside of said stick, a rib anchoring member mounted on said stick, a slidable member on said stick adapted to be slidable between the stationary locking member and the rib anchoring member, a complementary keeper, means to lock said umbrella in either open or closed position, said means including a double hook pivotally mounted on said slidable member to engage said complementary keeper, said keeper having a lower portion thereof tightly gripping the outside of said stick and the upper portion of said keeper expanded away from said stick, and one of said hooks being adapted to move inside of said expanded portion effecting detachable locking engagement with said keeper.

ANNA L. CAMPBELL.
